(57) CLAIM

The ornamental design for a scrapbooking workstation, as shown and described.

DESCRIPTION

FIG. 1 is a perspective view of a scrapbooking workstation showing my design;

FIG. 2 is a front view thereof;

FIG. 3 is a top plan view thereof;

FIG. 4 is a right side view thereof;

FIG. 5 is a back view thereof;

FIG. 6 is left side view thereof; and,

FIG. 7 is a bottom plan view thereof.

The broken lines shown in the drawing are for illustrative purposes only and form no part of the claimed design.
